UNITED STATES PATENT OFFICE.

GEORGE R. DAVIS, OF CLEVELAND, OHIO.

CENTRIFUGAL DRIER.

Application filed October 25, 1924. Serial No. 745,816.

This invention relates to centrifugal driers and more particularly to means for operating the discharge valve in the baskets of centrifugal driers, and has for its object the provision of improved power means for operating such valves.

Heretofore the discharge valve of centrifugal driers of the class to which this invention pertains, has generally been hand operated and considerable labor has been necessary at times to open it, due to packing of the dried material.

The present invention provides a fluid operated cylinder which is connected to the valve so as to open and close the same when fluid is admitted to the cylinder.

In the drawings, Figure 1 is a vertical sectional elevation through a drier embodying this invention.

Figure 2 is a plan view thereof.

Figure 3 is a fragmentary sectional view on the line III—III of Figure 1.

Referring more particularly to the drawings, the letter A designates the housing 25 stand, as a whole, of a well known form of drier, which stand consists generally of a base member 2 and spaced side members 3 and 4. An engine 5 is mounted on the base 2 for furnishing the power to operate the 30 drier.

The forward ends of the side members 3 and 4 are joined and support a suitable bearing 6 for the spindle or centrifugal shaft 7 which supports the perforated drier basket 35 8 at its lower end. The basket 8 is mounted within an imperforate stationary casing 9 adapted to catch or intercept the fluid thrown off by the centrifugal basket 8.

The bottom wall 10 of the basket 8 is 40 provided with a centrally arranged discharge opening 11 adapted to be normally closed by a bell shaped valve or closure 12. The bell shaped valve 12 is provided with a hollow tubular stem 13 and is mounted on the 45 spindle or shaft 7 so as to rotate therewith and have a vertical sliding movement on said shaft to open and close the opening 11.

The upper end of the stem 13 is provided 50 with a pair of spaced collars or flanges 15 between which a yoke 16 is loosely mounted.

The yoke 16 is provided with a rearwardly and upwardly offset connecting arm 17 adapted to extend above the upper edge of the casing 9 when the valve 12 is in its lowest or closed position. A connecting or

operating rod 18 has its lower end secured to the arm 17 and its upper end secured to the piston 19 of a fluid operated cylinder 20.

The cylinder 20 is disposed vertically between the side members 3 and 4 of the housing A and is supported at its lower end by a cross brace 21 extending between the members 3 and 4 and at its upper end by braces 22 and 23 which extend upwardly from the upper faces or flanges of the members 3 and 4 to the upper end of the cylinder.

A suitable guide bar 25 is arranged vertically at the rear of the rod 18 and has its upper end secured to the cross brace 21, 70 while its lower end is secured to the members 3 and 4 of the housing A. The rear end of the connecting arm 17 is provided with a roller 27 adapted to engage the guide bar 25 so as to steady and guide the yoke 16 75 during its vertical travel.

Fluid is adapted to be supplied to the cylinder 20 through a supply pipe 28 which connects through a four-way valve 29 with the combined inlet and exhaust pipes 30 and 31 leading to the opposite ends of the cylinder.

In order to prevent sudden jarring of the operating mechanism and valve, if the fluid should be exhausted from the cylinder 20 suddenly, I provide cushion springs 32 and 33 at the opposite ends of the cylinder against which the piston 19 will strike.

The operation of this device will be readily apparent. When it is desired to lift the valve 12 to discharge dried material from the basket 8, fluid will be admitted to the lower end of the cylinder 20, thereby forcing up the piston 19 and lifting the valve 90 through the connecting rod 18 and yoke 16. 95 When it is desired to again lower the valve 12 the control valve 29 will be turned so as to admit fluid to the upper end of the cylinder 20 and allow the discharge or exhaust 100 of the fluid from the lower side of the piston 19, thereby forcing the piston and lowering the valve 12.

I provide the yoke 16 with considerable clearance between its face and the stem 13 of the valve so that if the basket oscillates 105 when rotating, it will be free to strike the wooden buffer ring 35 located in the lower end of the casing 9, thus preventing springing of the power shaft 7.

While I have shown and described only 110

one specific embodiment of my invention, it will be understood that I do not wish to be limited thereto since various modifications may be made without departing from the scope of my invention as defined in the appended claims.

I claim—

1. In a centrifugal drier, the combination with a basket having a centrally arranged discharge opening in its bottom wall, and a vertically movable valve for closing said opening and adapted to be lifted to permit the discharge of material through said opening, of an operating rod having an operative connection with the upper end of said valve, said connection being adapted to permit free rotation and limited oscillation of said valve relative to said rod, and power means for reciprocating said rod to open and close said valve.

2. In a centrifugal drier, the combination with a basket having a centrally arranged discharge opening in its bottom wall, and a bell-shaped vertically movable valve for closing said opening and adapted to be lifted to permit the discharge of material through said opening, of a pair of flanges on the upper end of the stem of said valve, a yoke loosely mounted between said flanges, said yoke being adapted to permit free rotation and a limited horizontal oscillation of said valve stem relative to said yoke, an operating rod connected to said yoke, and power means for reciprocating said rod to open and close said valve.

3. In a centrifugal drier, the combination with a basket having a centrally arranged discharge opening in its bottom wall, and a bell-shaped vertically movable valve for closing said opening and adapted to be lifted to permit the discharge of material through said opening, of a pair of flanges on the upper end of the stem of said valve, a yoke loosely mounted between said flanges, said yoke being adapted to permit free rotation and a limited horizontal oscillation of said valve stem relative to said yoke, an operating rod connected to said yoke, means for guiding the lower end of said rod, and a fluid operated cylinder having its piston connected to the upper end of said rod for reciprocating said rod to open and close said valve.

4. The combination with a centrifugal drier comprising a housing, a vertical shaft having its upper end journaled in said housing, a basket secured to the lower end of said shaft having a centrally arranged discharge opening in its bottom wall, and a bell-shaped vertical movable valve slidably mounted on said shaft for closing said opening and adapted to be lifted to permit the discharge of the dried material through said opening, of a pair of flanges on the upper end of said valve, a yoke loosely mounted

between said flanges, said yoke being adapted to permit free rotation and a limited horizontal oscillation of said valve relative to said yoke, an operating rod connected to said yoke, means for guiding the lower end of said rod, and a fluid operated cylinder mounted on said housing and having its piston connected to the upper end of said rod for reciprocating said rod to open and close said valve.

5. The combination with a centrifugal drier comprising a housing, a vertical shaft having its upper end journaled in said housing, a basket secured to the lower end of said shaft having a centrally arranged discharge opening in its bottom wall, and a bell-shaped vertically movable valve slidably mounted on said shaft for closing said opening and adapted to be lifted to permit the discharge of the dried material through said opening, a valve stem extending upwardly from said valve, of a pair of flanges on the upper end of said valve stem, a yoke mounted between said flanges, an operating rod connected to said yoke, means for guiding the lower end of said yoke, a fluid operated cylinder mounted on said housing and having its piston connected to the upper end of said rod for reciprocating said rod to open and close said valve, means for controlling the operation of said cylinder, and means for cushioning the stroke of said piston at the termination of its travel so as to prevent the jarring of said valve.

6. The combination with a centrifugal drier comprising a housing, a vertical shaft having its upper end journaled in said housing, a basket secured to the lower end of said shaft having a centrally arranged discharge opening in its bottom wall, and a bell shaped vertically movable valve slidably mounted on said shaft for closing said opening and adapted to be lifted to permit the discharge of the dried material through said opening, a hollow sleeve-like valve stem extending upwardly from said valve and around said vertical shaft, of a pair of flanges on the upper end of said valve stem, a yoke mounted between said flanges, an operating rod connected to said yoke, means for guiding the lower end of said yoke, power means mounted on said housing and connected to said rod for reciprocating said rod to open and close said valve, means for controlling the operation of said power means, and means for preventing the jarring of said valve.

7. The combination with a centrifugal drier comprising a housing, a vertical shaft having its upper end journaled in said housing, a basket secured to the lower end of said shaft having a centrally arranged discharge opening in its bottom wall, and a bell shaped vertically movable valve slidably mounted on said shaft for closing said

opening and adapted to be lifted to permit the discharge of the dried material through said opening, a hollow sleeve-like valve stem extending upwardly from said valve and around said vertical shaft, of a pair of flanges on the upper end of said valve stem, a yoke mounted between said flanges, said yoke being loosely fitted around said valve stem so as to permit free rotation and a limited oscillation of said valve relative to said yoke, an operating rod connected to

said yoke, a guide-bar secured to said housing, a roller journaled on said yoke and adapted to ride on said bar when said valve is moved to open or close said discharge opening, and power means mounted on said housing and connected to said rod for reciprocating said rod to open and close said valve.

In testimony whereof, I have hereunto signed my name.

GEORGE R. DAVIS.
